UNITED STATES PATENT OFFICE.

JOHN B. SHUFELDT, JR., OF NEW YORK, N. Y., ASSIGNOR OF ONE-HALF TO JAMES B. ALLEN, OF BEDFORD PARK, NEW YORK.

LINOTYPE-MACHINE OR THE LIKE.

1,160,776.

Specification of Letters Patent. Patented Nov. 16, 1915.

Application filed April 20, 1914. Serial No. 833,162.

To all whom it may concern:

Be it known that I, JOHN B. SHUFELDT, Jr., of New York, in the county of Bronx, and in the State of New York, have invented a certain new and useful Improvement in Linotype-Machines or the like, and do hereby declare that the following is a full, clear, and exact description thereof.

My invention relates to an improvement 10 in linotype machines or the like and has for its object to provide a simplified keyboard for such machines.

In linotype machines in commercial use, a 15 separate key must be pressed for upper case and for lower case letters of the same kind, the pressing of each key releasing a single matrix from the magazine, from whence it is carried by a matrix belt to an assembler. This necessitates a large keyboard which is 20 complicated and difficult to learn, and which it is almost impossible to operate by the touch system on account of its size. No successful or practical mechanism for releasing the matrices by a simpler keyboard has been 25 devised, to my knowledge, previous to my invention. The embodiment of my invention disclosed herein releases the desired matrix accurately and surely under all conditions of operation, and may be adapted 30 readily to linotype or similar machines already in use, with comparatively simple adjustments thereof.

Referring to the drawings, Figure 1 is a 35 side elevation; and Fig. 2 is a diagram of one method of wiring, closed circuits being indicated in full lines.

Similar reference characters refer to similar parts throughout the drawings.

Although my invention has been shown 40 applied to a double-magazine linotype, commonly called a "double-decker," it is not to be limited to this type of machine, which was chosen to illustrate my invention solely because it is possible in this type to show a 45 side view of two separate magazine channels conveniently and without confusion. My invention is applicable to all kinds of linotype or similar machines and operates with equal certainty and precision with all designs and types.

The magazine, the matrix, and the matrix-escapement for holding and releasing the matrix, may be the same as in present types of commercial linotype or similar ma-

chines, but may, however, be changed or 55 modified when used with my invention, to meet varied conditions or improvements in such machines. The ordinary matrix-escapement mechanism illustrated consists of two vertical pawls 1 and 2 which project 60 through the under side of the magazine and engage the ears of the matrices. The pawls for each matrix are seated in a verge 3 which is pivoted at its center so that when one pawl is raised the other is lowered. The 65 verge is operated by the keyrod 4 which hooks into the verge in well known manner as shown.

The spring 5, mounted on keyrod 4 between a head on the end thereof and a guide 70 frame connected to a stationary part of the machine, tends to keep the pawl 1 in engagement with an ear of the lower matrix. When the key is pressed the verge rocks on its pivot, thereby retracting pawl 1 and advancing pawl 2. This allows the lower matrix to escape and holds the following matrix in the magazine. When the key is released the pawls return to the first position above described, the following matrix becoming the lower matrix and in position to be released upon pressing the key as before.

In the embodiment chosen for illustration, instead of connecting the operating key to the keyrod by mechanical means as in the 85 present type of linotype or similar machines, I provide electrical connecting means consisting of an electrical circuit containing a source of electrical power, operating keys to close the circuits, and magnets or solenoids adapted to act upon the keyrods and thereby operate the matrix escapement. A magnet is provided for each keyrod, and they may be arranged in any position or relation to secure economy of space. For 95 convenience of illustration, magnet 6^a will be considered as controlling the matrix escapement of a matrix bearing the letter "a," and the magnet 6^A as controlling the matrix escapement of a matrix bearing the letter "A." In the embodiment of my invention illustrated, one key 7 on the keyboard controls both these magnets. When said key 7 is pressed alone it releases a matrix bearing the letter "a," but when pressed 100 in connection with master-key 8 it releases the matrix bearing the letter "A." Each key on the keyboard in like manner will

control two matrices, releasing one matrix when pressed alone, and releasing the other matrix, when pressed in connection with the single master key 8.

- 5 Referring to Fig. 2, full lines indicate a circuit including magnet 6^a, a source of electrical power indicated at 9, and an operating key 7 adapted to close the circuit when pressed. The closing of the circuit energizes magnet 6^a which in the illustration will cause the release of a matrix bearing the letter "a." When key 8 is pressed in connection with key 7, the circuit through magnet 6^a is broken at 10 and completed at 11, 10 thereby closing the circuit indicated by dot and dash lines (which normally is open) and energizing magnet 6^a which, in the illustration, will cause the release of a matrix bearing the letter "A."
- 15 20 In order that the touch of the machine may be adjusted to suit the operator, adjusting screws 12 and 13 are provided as shown in Fig. 1, which controls the distance which each key must move when pressed to control 25 the circuits in the manner above indicated.

It is evident that other embodiments of my invention will be apparent to those skilled in the art without departing from the scope thereof, or from the scope of my 30 claims, it being my intent to provide a simple and effective device whereby each key on the board controls two matrices, one matrix being released when the key is operated alone and the other matrix being released 35 when the key is operated in conjunction with the master key.

Having disclosed one embodiment of my invention what I claim is:

1. In a linotype machine, a key, a master key, two matrix escapements, means to operate one matrix escapement when one key is pressed, and means to operate the other escapement when both keys are pressed simultaneously. 40
2. In a linotype machine, a key, a master key, two matrix escapements, electrical means to operate one matrix escapement when one key is pressed, and means to operate the other escapement when both keys are pressed 45 simultaneously.
3. In a linotype machine, a key, a master key, two matrix escapements, means to operate one matrix escapement when one key is pressed, and means to operate the other escapement when both keys are pressed simultaneously comprising a magnet operating each escapement. 50
4. In a linotype machine, a key, a master key, two matrix escapements, and means to operate said escapements comprising two magnets one of which is energized when one key is pressed, and the other of which is energized when both keys are pressed simultaneously. 55
5. In a linotype machine, a key, a master 60

key, two matrix escapements, and means to operate said escapements comprising two magnets, means to energize one of said magnets by closing a circuit controlled by one key, and means to energize the other magnet 70 by pressing both said keys whereby the first circuit is opened and a new circuit closed.

6. In a linotype machine, a key, a master key, two matrix escapements, means to operate one matrix escapement when one key is 75 pressed, means to operate the other escapement when both keys are pressed simultaneously, and means to adjust the movement of said keys.

7. In a linotype machine, a series of matrices, and means to release said matrices comprising a series of keys adapted to release one matrix when pressed alone and a different matrix when pressed simultaneously in connection with a single master key. 80

8. In a linotype machine, a series of matrices, and means to release said matrices comprising a single master key adapted to be pressed simultaneously with any one of a series of keys.

9. In a linotype machine, a series of matrices, and means to release said matrices comprising a plurality of electrical circuits, a key provided with means adapted to close selectively any of said circuits, and a second key provided with means adapted to close the circuit thus selectively closed.

10. In a linotype machine, a series of matrices, and means to release said matrices comprising a plurality of electrical circuits, a key provided with means adapted to close selectively any of said circuits, a second key provided with means adapted to close the circuit thus selectively closed, and wires connecting said means and so arranged that one circuit is closed when one key is in normal position and the second key is pressed and so that a different circuit is closed when both keys are pressed.

11. In a linotype machine, a series of matrices, and means to release said matrices comprising two electrical circuits, a key provided with two sets of circuit-closing means one set normally closed and the other set normally open, a second key provided with a set of circuit-closing means, and wires connecting the sets of circuit-closing means of said first key with the set of circuit-closing means of said second key.

12. In a linotype machine, a series of matrices, means to release said matrices comprising magnets, electrical circuits energizing said magnets comprising a key provided with means adapted to close selectively any of said circuits, and a second key provided with means adapted to close the circuit thus selectively closed.

13. In a linotype machine, a series of matrices, releasing devices for said matrices comprising key rods, a single key, and a master

key, each of which rods and keys is fixed in a single operative position and adapted to operate one releasing device when a single key is pressed and a different releasing device when said key and a master key are pressed.

In testimony that I claim the foregoing I have hereunto set my hand.

JOHN B. SHUFELDT, JR.
